[57] CLAIM

The ornamental design for a cutting insert, as shown.

DESCRIPTION

FIG. 1 is a perspective view of a cutting insert showing a form of our new design;

FIG. 2 is a top plan view of the cutting insert of FIG. 1;

FIG. 3 is a side view of the cutting insert of FIG. 1; and,

FIG. 4 is a view of one of the ends of the cutting insert of FIG. 1.

The broken line showing is for illustrative purposes only and forms no part of the claimed design.
